UNITED STATES PATENT OFFICE.

GEORGE WRIGHT, OF CHATHAM, ONTARIO, CANADA.

LAND-ROLLER.

1,270,087.

Specification of Letters Patent. Patented June 18, 1918.

Application filed August 5, 1916. Serial No. 113,403.

To all whom it may concern:

Be it known that I, GEORGE WRIGHT, a citizen of Canada, residing at Chatham, in the county of Kent and Province of Ontario, 5 Canada; have invented new and useful Improvements in Land-Rollers, of which the following is a specification.

My invention relates to improvements in land rollers; the objects thereof being to 10 provide a roller that will roll uneven ground with equal pressure whether it be a knoll or hollow.

The frame of my roller can be made lighter than ordinarily, as the draft is directly 15 from the rear in the middle between the two rollers; also, in my invention the rollers are closer together endwise, and therefore, leave a smaller ridge between the rollers.

I attain these objects in manner as illustrated in the accompanying drawings, in 20 which:

Figure 1 is a perspective view of the complete rollers;

Fig. 2 is a front view, the dotted lines 25 showing how each section acts on uneven ground;

Fig. 3 is a cross section of a single roller through 1—2 of Fig. 1;

Fig. 4 is an end view of roller with part 30 cut away showing the connection of the draw rod from tongue to rear;

Fig. 5 is a top view of outer end of shaft showing how journal is hung in frame;

Fig. 6 is an end view of shaft, journal and 35 pivots;

Fig. 7 is a side view of bracket hanger at outer end of rollers, showing how the journal moves back and forth as the inner end of rollers move up or down when passing over 40 uneven ground;

Fig. 8 is a side view of inner end of shaft with square box journal thereon, and

Fig. 9 is a top view thereof.

Similar letters refer to similar parts 45 throughout the several views:

Referring to Figs. 1 and 2, the rollers are shown in two sections, inclosed by a frame B which is made from heavy steel bars. To this frame are fastened standards B'. B' 50 near each end, and E in the middle projecting below the frame in front and rear, and having holes bored through said projections. On these standards is placed the platform C, supporting the seat D and also on which to 55 place additional weight if required. The

tongue is attached to the front at the standard E and braced to the frame B. Through the lower projections of the standard E a draw bolt or rod F. is placed, bolted to the tongue and extending to the rear of 60 frame B, where it is secured by jam nuts which hold the frame rigid; outside of the jam nut is a knuckle to which a small roller can be attached as shown in Fig. 4. This roller is to level down the small ridge left 65 between the large rollers. On each corner of frame B. are fastened brackets Q on which is hung a shaft K, having a right and left hand coiled spring firmly fastened at each end to a lever J, and in the middle to a 70 ratchet wheel L. which is kept taut by the tension rod M. fastened to the ends of frame B. The outer ends of the rollers A are hung directly from frame B. but the inner ends are hung to an inner frame H. which swings 75 in frame B. on lug pins G., Figs. 2 and 3. It is by means of these pins that the rollers are allowed to raise and lower as they go over uneven ground. It will readily be seen that when a roller strikes a knoll or high 80 spot it will rise and go over it, but when a hollow spot intervenes pressure will require to be applied to make it touch the low spots, and give an even bearing. This may be done in various ways, by placing weight on the 85 inner end, by automatic pressure or by a flat or coiled spring, of these plans I have adopted the coiled spring. To make the pressure effective I connect levers J and the ends of inner frame H. at R. with rods 90 I show in Figs. 1 and 2.

To enable the rollers to work freely over uneven ground the inner end of roller shaft N. Fig. 3, has a square boxing b having a center hole f in which the pivots of the 95 brackets a are inserted as shown in Figs. 8 and 9, said brackets being bolted to the inner frame H., part of boxing b is cut way in Fig. 9 to show the pivots in the boxing. The outer end of shaft N. revolves in a journal O, having pivots e, on each side, which hang in the slotted brackets P. attached to frame B. more fully shown in Figs. 5 and 6. The dotted lines in Fig. 7, show how the journal O moves back and forth as the inner 100 end of roller moves up or down. The boxing b and journal O. are kept in place with a key c at each end of the shaft N.

To operate the rollers, the coiled springs are set to the required tension and held in 110

place by a rod *m* catching over the ratchet wheel *L*, thus giving an even pressure on the inner end of rollers through the lever *J*, acting on the ends of frame *H*, as shown in Fig. 2, where the dotted lines of left hand roller show inner end as dropping into a hollow and those of right hand roller as going over a knoll, so that whether the rollers are going over high or low ground an even pressure is maintained.

As pressure is the special requisite in my invention I do not confine myself to the coiled spring but make my claims broadly.

What I claim as my invention and wish to secure by Letters Patent in sectional land rollers is:—

1. The combinations of right and left hand coiled springs encircling a shaft mounted on brackets secured to the outer ends of a main frame, one end of said springs being attached to a ratchet wheel set in the middle of said shaft with means to hold said springs in tension, their opposite ends being secured to levers projecting from the ends of said shaft; an inner frame comprising an end piece and arms projecting at right angles therefrom parallel with sides of main frame, with means to hang said inner frame from the said main frame, and connecting rods with means to connect the above mentioned levers by the said connecting rods to the ends of aforesaid inner frame.

2. The combination with a roller and frame of a square journal boxing at inner end of roller having a circular hole longitudinally through its center of sufficient size to admit the shaft of the roller with means to secure said boxing to inner ends of said shaft, and brackets secured to the frame, the outer ends of said brackets terminating in circular pivots that fit into perforations made on opposite sides of the square part of above mentioned journal boxing.

3. The combination with a roller of a round journal boxing at the outer end of roller having a hole bored longitudinally through its center of sufficient size to admit

the roller shaft, and having its middle part of oblong shape transversely terminating in round lugs at opposite sides, with means to secure said journal boxing to outer end of said shaft, and elongated slotted brackets in which the above mentioned lugs slide back and forth, with means to secure said brackets to the ends of a frame.

4. The combinations of rollers and a main frame with two inner frames consisting of an end piece at inner end of roller, and arms projecting outward parallel with sides of main frame, and having lugs to hang said inner frame from the main frame, right and left hand coiled springs encircling a shaft mounted on brackets secured to the outer ends of the main frame, the inner ends of said springs being attached to a ratchet wheel set in the middle of said shaft with means to hold said springs in tension, their opposite ends being secured to levers projecting from the ends of said shaft, connecting rods with means to connect the above mentioned levers by the said connecting rods to the ends of aforesaid inner frames, square journal boxings having a hole bored longitudinally through the center thereof of diameter sufficient to admit the shaft of the rollers with means to secure said boxing to inner ends of said shafts and brackets secured to the inner frame, the outer ends of said brackets terminating in circular pivots that fit in perforations made on opposite sides of the square part of above mentioned journal boxing; round journal boxings at the outer end of rollers having a hole bored longitudinally through its center of diameter sufficient to admit the roller shaft, and having its middle part of oblong shape transversely terminating in round lugs at opposite sides with means to secure said journal boxing to outer ends of said shaft, and elongated slotted brackets in which the above mentioned lugs slide back and forth with means to secure said brackets to the ends of main frame.

GEORGE WRIGHT.
